APPARATUS FOR CLEANING TANKS

Walter H. Bell, Port Arthur, Tex.

Application July 23, 1947, Serial No. 762,866

5 Claims. (Cl. 299—67)

1

This invention relates to apparatus for cleaning tanks, and more particularly to a machine for use in the interior of tanks of the character used on shipboard and elsewhere for the transportation and storage of oil, for the removal of oil, rust and other interior coatings and sludge, and for freeing the tanks of gas therein.

Various expedients have heretofore been proposed for cleaning tanks of the character aforesaid, but none of these have proven wholly satisfactory.

In accordance with the present invention, a tank cleaner is provided in which a plurality of jets of water are projected outwardly within the interior of the tank for cleaning, washing and the removal of gas therein.

In accordance with the present invention also, a tank cleaning machine is provided which is particularly suitable for use by relatively inexperienced operators, which will be effective in its cleaning operations, and which is operable from the water supplies available on oil tankers and the like.

In accordance with the present invention also, a tank cleaning machine is provided which is particularly suitable for cleaning the interior of ships' tanks, and in which a plurality of jets of water are projected outwardly and distributed over a wide area for this purpose.

Other objects and advantageous features of the invention will be apparent from the specification and claims.

The nature and characteristic features of the invention will be more readily understood from the following description, taken in connection with the accompanying drawings forming part hereof, in which:

Figure 1 is a side elevational view of a tank cleaner in accordance with the present invention;

Fig. 2 is a fragmentary vertical sectional view, enlarged, showing certain of the interior details, parts being broken away; and

Fig. 3 is a horizontal sectional view taken approximately on the line 3—3 of Fig. 2.

It should, of course, be understood that the description and drawings herein are illustrative merely, and that various modifications and changes may be made in the structure disclosed without departing from the spirit of the invention.

Referring more particularly to the drawings, in which a preferred embodiment of the invention is illustrated, a vertical tube 10 is provided which serves as a support, as hereinafter explained, and which is adapted to be connected in any pre-

ferred manner to a source of water, hot or cold as desired, and under pressure. The tube 10 is provided with a radially disposed bearing and supporting flange 11 which is secured thereto in any desired manner.

The tube 10 is in communication with the interior of a casing 12. The casing 12 is preferably made in a plurality of separable sections, such as an upper dome shaped section 13, a central cylindrical section 14, and a lower semi-spherical section 15. The upper casing section 13 is preferably provided with a flange 16 at the inner end of which a groove 17 is provided for the reception of the upper end of the central casing section 14. The lower casing section 15 is also preferably provided with a flange 19 and with a groove 20 in which the lower end of the central casing section 14 is adapted to be received. The joints between the casing sections 13 and 14 and 20 between the casing sections 14 and 15 are preferably of a character to prevent fluid leakage at these locations.

Stay bolts 21, extending through the flanges 16 and 19, are provided for holding the casing sections 13, 14 and 15 in assembled relationship, and permit of access to the interior of the casing 12, if desired.

At the upper end of the upper casing section 13, a cylindrical neck portion 24 is provided having at the upper end thereof an outwardly extending portion 25 provided at the periphery thereof with a cylindrical upwardly extending rim 26 from which a horizontally disposed connecting flange 27 extends. A bearing plate 28 is also provided and is adapted to be secured by bolts 29 to the flange 27 in fluid tight relationship. A sealing gland 30 is provided on the upper part of the bearing plate 28. A packing compressing ring 31 is mounted on the gland 30 and in engagement with a suitable ring packing 32 interposed between the ring 31 and the gland 30.

The engagement of the ring packing 32 with the exterior of the tube 10 upon adjustment of the ring 31 prevents fluid leakage past the packing ring 31 in either direction.

A thrust bearing 35 is mounted within the rim 26 between the bearing end plate 28 and the flange 27 on the pipe 10 for supporting the casing 12 and the structure carried thereby and permitting rotation of the casing 12 with respect to the pipe 10.

Within the upper portion of the casing 12 and surrounding the tube 10, a box 40 is provided. The box 40 preferably has a securing rim 41 at the upper end thereof for removably securing the box 40 to the casing 12 in fluid tight relationship,

bolts 44 being utilized for this purpose. At the lower end of the box 40, a packing gland 37 and packing compressing ring 42 are provided, suitable ring packing 43 being interposed between the ring 42 and the gland 37 and in engagement with the tube 10 for preventing fluid leakage past the packing 43.

On one side wall of the box 40 an impeller wheel chamber 45 is provided. In one side wall of the chamber 45 a fluid inlet nozzle 46 is provided in communication with the interior of the casing 12 and with the interior of the chamber 45. Another side wall of the chamber 45 has a fluid discharge conduit 47 extending therethrough and through the exterior wall of the casing 12 for fluid discharge, as hereinafter explained.

Within the impeller wheel chamber 45 an impeller wheel 48 is mounted carried on a shaft 49 for actuation by fluid delivered through the nozzle 46 and discharged through the conduit 47. A packing gland 50 is provided for preventing fluid leakage into the interior of the box 40.

Within the interior of the box 40 a pinion 55 is provided on the shaft 49 and is in engagement with a gear 56 mounted at one end of a shaft 57, the other end of the shaft 57 having a worm 58 thereon for engagement by a pinion 59 carried on one end of a shaft 60. The shaft 60 has a worm 61 carried thereon with which a pinion 62 carried on a shaft 63 is in engagement, the shaft 63 also having a worm 64 thereon for engagement with a gear 65 welded or otherwise secured to the exterior of the tube 10. The shafts 49, 57, 60 and 63 may be supported by suitable bearings 66. The tube 10 being held against rotation, the casing 12 is thus rotated upon rotation of the impeller wheel 48 on the shaft 49.

The upper casing section 13 has, in the wall thereof, a plurality of fluid discharge nozzles 70 in communication with the interior of the casing 12, the nozzles 70 being disposed at different angles above the horizontal for discharging washing and cleaning fluid in jets.

The central casing section 14 also has, in the wall thereof, a plurality of fluid discharge nozzles 71 in communication with the interior of the casing 12, the nozzles 71 preferably being disposed at different levels, for discharging washing and cleaning fluid in jets. The discharge conduit 47 preferably also extends through the wall of the casing section 14.

The lower casing section 15 also has, in the wall thereof, a plurality of fluid discharge nozzles 72 in communication with the interior of the casing 12, the nozzles 72 preferably being disposed at different levels below the horizontal for discharging washing and cleaning fluid in jets.

The mode of operation will now be pointed out.

Water under pressure from the ship's pumps or from any other suitable source of pressure, and hot or cold as desired, is supplied to the tube 10. The tube 10 and the casing 12 carried thereby are lowered about one-third of the way down into the tank to be cleaned. Water under pressure delivered through the tube 10 to the interior of the casing 12 is supplied through the fluid inlet nozzle 46 for effecting rotation of the impeller wheel 48. The water from the impeller wheel 48 is discharged through the fluid discharge conduit 47 toward the tank walls.

Rotation of the impeller wheel 48 is effective, through the shaft 49 and the gear train against an abutment provided by the gear 65 on the tube 10. The tube 10, being held against rota-

tion, the casing 12 is caused to be rotated, the thrust bearing 35 permitting this movement.

Fluid is discharged from the interior of the casing through the nozzles 70, 71 and 72 in a plurality of jets at different angles. The jets of water from the nozzles 70, 71 and 72 strike the walls of the tank and loosen and remove the oil and rust which is thus delivered to the bottom of the tank for removal. After the casing 12 has been rotated in this manner for about twenty to thirty minutes, it is then lowered to a location about half way down the tank and rotated for about the same period of time with the cleaning jets of liquid delivered from the nozzles 70, 71 and 72. The pipe 10 and the casing 12 carried thereby are then lowered to about two-thirds of the way down in the tank and again operated with liquid jets discharged from the nozzles 70, 71 and 72 until the cleaning of the tank is completed. The discharge of the water in a plurality of rotating jets directed against the sides of the tank at various angles also tends to remove gases in the tank. The nozzles in the lower casing section 15 also act to keep the water in the lower part of the tank being cleaned in an agitated condition, thereby further aiding in the cleaning.

I claim:

1. Tank cleaning apparatus comprising a fluid delivery tube adapted to be lowered in a tank, a hollow casing having an interior chamber with which the lower end of said tube is in communication, members for rotatably supporting said casing on the lower end of said tube, said casing having a plurality of fixedly mounted nozzles extending from the interior chamber and through the wall thereof for simultaneous discharge of a plurality of jets of fluid, a closed compartment in said interior chamber and having a fluid inlet in communication with said interior chamber and a fluid discharge passageway extending through the wall of said casing, a fluid actuated motor in said compartment interposed between said inlet and discharge passageway, and driving connections between said motor and said tube including a ring gear fixed on said tube and a gear driven by said motor in engagement therewith for effecting rotation of said casing with respect to said tube.

2. Tank cleaning apparatus comprising a fluid delivery tube adapted to be lowered into a tank, a hollow casing having an interior chamber with which the lower end of said tube is in communication, members for rotatably supporting said casing on the lower end of the said tube, said casing having a plurality of fixedly mounted nozzles extending from the interior chamber through the wall thereof for simultaneous discharge of a plurality of jets of fluid, a fluid-tight compartment in said casing, a second compartment carried by said first compartment, said second compartment having a fluid inlet in communication with said interior chamber and a fluid discharge passageway in communication with the exterior of said casing, a fluid actuated motor in said second compartment and interposed between said fluid inlet and said fluid discharge passageway, and power transmitting means in said first compartment connecting said motor and said tube including a ring gear fixedly mounted on said tube and a gear driven by said motor in engagement therewith for effecting rotation of said casing with respect to said tube.

3. Tank cleaning apparatus comprising a tubular fluid delivery member adapted to be lowered

into a tank, a hollow casing member having an interior chamber with which the lower end of said tubular member is in communication, members for rotatably supporting said casing on the lower end of said tubular member, said casing having a plurality of fixedly mounted nozzles extending from said chamber through the wall thereof for simultaneous discharge of a plurality of jets of fluid, an enclosure fixedly mounted with respect to said casing and spaced above the terminus of said tubular member and surrounding a portion of the lower end of said tubular member, a fluid motor in said enclosure, a connection from said interior chamber for supplying fluid for actuating said fluid motor and a connection to the exterior of said casing for the discharge of the motor actuating fluid, and transmission members in said enclosure including an engageable abutment member on said tubular member and a member in engagement therewith and operated by said motor for effecting rotation of said casing with respect to said tube.

4. Tank cleaning apparatus comprising a tubular fluid delivery member adapted to be lowered into a tank, a hollow casing member enclosing the lower end of said tubular member and having an interior chamber with which the lower end of the tubular member is in communication, members for rotatably supporting said casing on the lower end of said tubular member, said casing having a plurality of fixedly mounted nozzles extending from said interior chamber through the wall thereof for simultaneous discharge of a plurality of jets of fluid, an enclosure in said interior chamber fixedly mounted with respect to said casing and disposed above the lower end of said tubular member, members for preventing fluid leakage into the interior of said enclosure, a fluid motor in said enclosure, a fluid connection from said interior chamber for supplying fluid for ac-

tuating said fluid motor and a fluid connection to the exterior of said casing for the discharge of the motor actuating fluid, a ring gear in said enclosure fixedly mounted on said tubular member, and a member operated by said motor and in engagement with said ring gear for effecting rotation of said casing with respect to said tube.

5. Tank cleaning apparatus comprising a tubular fluid delivery member adapted to be lowered into a tank, a hollow sectional casing member enclosing the lower end of said tubular member and having an interior chamber, members for rotatably supporting said casing member with respect to the lower end of said tubular member, 10 said casing member including a lower section having a plurality of fixedly mounted fluid discharge nozzles extending downwardly through the wall thereof and an upper section, a fluid motor in said upper section, a fluid connection from said interior chamber for supplying fluid for actuating said fluid motor, a fluid connection for the discharge of the motor actuating fluid, a ring gear fixedly mounted on said tubular member in said upper section, and driving connections in said upper section between said motor and said ring gear for rotating said casing member with respect to said tubular member.
